UNITED STATES PATENT OFFICE

FLORENCE B. MYERS, OF LOS ANGELES, CALIFORNIA

DESIGN FOR A HOSE LEAK STOP

Application filed December 30, 1931. Serial No. 42,321. Term of patent 14 years.

To all whom it may concern:

Be it known that I, FLORENCE B. MYERS, a citizen of the United States, residing at Los Angeles, in the county of Los Angeles and State of California, have invented a new, original, and ornamental Design for Hose Leak Stops, of which the following is a specification, reference being had to the accompanying drawing.

Figure 1 is a perspective view of the hose leak stop, showing it in the closed position. Figure 2 is a perspective view of the opposite side of the device, also in the closed position.

I claim:

The ornamental design for a hose leak stop, as shown.

FLORENCE B. MYERS.
